UNITED STATES PATENT OFFICE.

ARTHUR W. SAVAGE, OF SAN DIEGO, CALIFORNIA.

TOY MACHINE GUN.

1,419,646.

Specification of Letters Patent. Patented June 13, 1922.

Application filed April 2, 1921. Serial No. 457,907.

To all whom it may concern:

Be it known that I, ARTHUR W. SAVAGE, a citizen of the United States, residing at San Diego, in the county of San Diego and 5 State of California, have invented new and useful Improvements in Toy Machine Guns, of which the following is a specification.

This invention relates to detonating apparatus, and particularly to a toy machine gun 10 made in simulation of a standard form of machine gun such as is used by the United States Army.

The invention has for an object the provision of a toy machine gun which will afford maximum amusement and at the same 15 time is instructive from a scientific standpoint.

In practicing the invention I provide a two-part casing member made to resemble a 20 machine gun barrel. Within this casing member or barrel are provided elements which are adapted to advance and fire a percussion cap tape. Various other elements that go to make a complete whole in machine 25 gun structure are likewise provided.

The invention has for further objects the provision of an improved toy machine gun which will be simple and inexpensive in construction, and in addition durable and 30 efficient in its operation.

With the above mentioned and other objects in view, the invention consists in the novel and useful provision, formation, construction, combination, association and 35 inter-relation of parts, members and features, all as illustrated in some of its embodiments in the accompanying drawing, described in the following detailed description, and finally pointed out with particularity in the 40 claims.

In the drawing:

Figure 1 is a perspective view of a toy machine gun;

Figure 2 is a fragmentary view of the machine gun shown in Figure 1, and showing the internal mechanism for feeding the paper roll containing spaced percussion caps, and for firing the same;

Figure 3 is a fragmentary cross sectional view of the machine gun, taken on the line 3-3 of Figure 2, and looking in the direction of the appended arrows;

Figure 4 is a fragmentary view, certain parts being shown in section, of a tripod of 55 the machine gun, and taken on the line 4-4

of Figure 2, looking in the direction of the appended arrows.

Corresponding parts in all the figures are designated by the same reference characters.

Referring with particularity to the drawing, A designates a toy machine gun in its entirety, of which a is the barrel member and b the tripod supporting the barrel member, both of which elements are used in practicing one embodiment of my invention. 60 The barrel member a includes a two-part casing 1 and 2, which casings are hollowed out on their interior surfaces in such a manner as to provide a muzzle opening 3 and likewise to provide for maintaining the various operating mechanisms used in practicing the invention. The barrel a is so arranged that the casing members 1 and 2 may be accurately fitted together and conveniently 65 maintained in position by means of screws 4 passing through perforations in the casing 2 and having engagement with screw-threaded perforations in the casing 1, as shown at 70 5 and 5a.

A tape c is carried on a pivot pin 6 joined 80 to a lug member 7 upon the casing 2. Said tape member c is adapted to be rolled into a compact mass and fitted over the pin 6 and to have a longitudinal stretch thereof advanced through a feed port 8 within the barrel member a. The tape c may comprise an extended strip of paper carrying longitudinal percussion caps 9 thereon.

As has been stated, each of the casing 90 members 1 and 2 is hollowed on its interior surface in such a manner as to confine the firing and feeding mechanism, and said firing mechanism may comprise a hammer d and a member e adapted to perform a double purpose; that is, to advance the tape c and 95 likewise control movement of the hammer member d. There is likewise provided within the barrel an anvil plate f, which anvil plate is carried by the casing 2 by means of a rivet or screw 10 passing through perforations in the casing 2 and anvil f. A spring member 11 is likewise joined with the anvil plate f and held in position by means of the rivet 10. The means e may comprise a wheel member provided with teeth or heads 12, 100 said heads being provided with blunt noses 13. The means e is carried upon a leg 14 of a hand crank g, which hand crank is adapted to pass through aligned perforations in the casings 1 and 2, as shown at 15 110

and 16. The means *e* may be conveniently retained on the leg 14 by having the leg carry a projecting pin member 17 adapted to be confined within a radial slot 18 of the means *e*. The particular shape of the interior surface of the casings 1 and 2 is such as to confine the means *e* between two projections 19 and 20, as shown in Fig. 3. The means *e* is adapted to have its heads 12 engage with the spring member 11, as shown in Figure 2.

As stated the tape *c* may be advanced through the feed port 8 formed by the two casings 1 and 2. In this connection it may be said that the casing 2 has a projection 21 extending within a grooved portion 22 of the casing 1 and this projection 21 would help to prevent displacement of the tape member *c*.

20 The member *c* has a length thereof, as 23, advanced through the feed port 8 and a portion thereof interposed between the spring 11 and certain of the teeth or heads 12 of the means *e*, as shown at 24, and a further portion interposed between a face of the anvil plate *f* and a face of the hammer *d*, the remainder of the tape being passed through an outlet opening between the casings 1 and 2. Each casing is given a half ring bore, as 30 shown at 25 so that when the casings are held in joined relation, as illustrated in Figure 1, there will be a circular bore extending through the casing elements. Within said bore is adapted to be confined a 35 coil spring 26, which coil spring is adapted to engage a portion, as 27, of the hammer *d* and urge same against the anvil plate *f*, as shown at 28. It may be well to mention at this time that the hammer *d*, the means *e* 40 and the anvil plate *f* are all carried between the projections 19 and 20 of the casings 1 and 2. This is mentioned for the reason that it is necessary to properly align the firing mechanism of the toy gun so that 45 the tape will be properly fired at all times. Likewise the portions 19 and 20 only extend a certain distance, as 29, within the casings 1 and 2, and the remaining portions of the casings are hollowed to the muzzle. The 50 barrel *a*, as has been stated, is shaped to resemble the barrel of a machine gun and has a curved portion, as 30, with the remainder of the barrel having its top portion triangular, as 31, while its bottom portion is 55 likewise triangular, as at 32, as far as the point 33 forming what might be termed a base. This base is mounted upon a curved member 34. Said member is shown in the form of a frustum of a cone. However, any 60 other form would perform the purpose required.

Referring to Figures 2 and 4 the member 34 is provided with three slotted portions 35, 36 and 37. The tripod, which comprises 65 leg members 38 provided with angularly

directed portions, are adapted to have their angularly directed portions as 39 confined within the slotted portions 35, 36 and 37. A bolt member 40 passes through a perforation in the barrel *a* and through a perforation in the member 34. A wing nut 41 screws upon said bolt member 40, and has its base 42 bearing against the angularly directed portions 39 of each of the leg members 38. It will thus be seen that the leg members may be conveniently held in a locked position to the member 34 and firmly support the barrel member *a*. The casing 1 may likewise be provided with an outstanding stud 7^a similar to the lug or projection 7 on the casing 2, so as to positively confine the tape *c*. One of the casing members may be provided with an aiming arm *h*, so that the barrel of the toy machine gun may be swung into various positions. 85

The operation is as follows:

After the tape member *c* has had a stretch of the same advanced between the spring 11 and the member *e* and likewise between the anvil *f* and the hammer *d*, a rotation of 90 the hand crank *g* will tend to advance the tape member *c* inwardly of the barrel member *a*, due to the pinching relation that exists between the teeth 12 and the spring 11. As the means *e* rotates the teeth 12 have a 95 face thereof, as 43, adapted to engage a nose portion as 44 on the hammer *d*. A rotation of the means *e* will then tend to pivot the hammer *d* downwardly upon its pivot pin 6 and depress the coil spring 26. When the 100 means *e* has rotated sufficiently the face 43 will slide from the nose 44 and allow the hammer to strike the tape *c* against the anvil plate *f*, due to the force exerted upwardly by the coil spring 26 against the hammer *d*. The coil spring 26 therefore, if strong enough, will detonate a percussion-cap on the tape member *c*. The spent portion of the tape, as 45, will be ejected from a point, as 46. 105

It will be observed that the member *e* is 110 so adapted to co-operate with the hammer *d* as to prevent retrograde movement of the tape *c*; that is, the face portion 43 prevents counter-rotation of the hand crank *g*, as it comes into contact with one of the teeth 12, and only tend to urge the hammer *d* against the anvil plate *f*. The manner in which the tape is advanced causes the tape to be advanced between the hammer and the anvil plate at an angle, and this tends to deflect 115 the fire of an exploded cap so as to prevent premature ignition of an unexploded cap. 120

It will be noticed that the spring member 11 at all times engages certain of the teeth or heads 12 of the means *e*, while the hammer *d* and the anvil *f* do not at all times engage the tape. This fact permits the tape to be properly fed toward the hammer so as to detonate each successive percussion-cap contained thereon. 125 130

It is obvious that many changes and variations and modifications may be made in departure from the particular description and showing of the accompanying drawing, in 5 adapting the invention to varying conditions and requirements of use and service, without departing from the true spirit of the invention.

Having thus disclosed my invention, I 10 claim and desire to secure by Letters Patent:

1. A toy machine gun including a barrel consisting of hollow complemental sections forming a mechanism chamber at the breach end thereof, said sections also having a feed 15 port, lugs offset from the breach ends of said sections adjacent the feed port, and detonating means arranged within said mechanism chamber, said means comprising a toothed trigger and feeding wheel, a tension- 20 ing spring cooperating therewith, an anvil, and a spring tensioned hammer for engaging said anvil and adapted to be actuated by the said toothed wheel.

2. A toy machine gun including a barrel

consisting of complemental sections ar- 25 ranged to form a mechanism chamber having a feed opening, magazine reel-supporting lugs projecting longitudinally from the breach end of the barrel adjacent said feed port, and combined feeding and detonating 30 means arranged within said chamber.

3. A toy machine gun including a barrel consisting of complemental casing sections assembled to provide a mechanism chamber and having complemental cut-away portions 35 at the breach end for providing an opening for the cap tape, lugs offset from the breach end of the said sections and providing journal supports for a reel of cap tape, and combined feeding and detonating 40 means arranged within said chamber.

In testimony whereof, I have signed my name to this specification in the presence of two subscribing witnesses.

ARTHUR W. SAVAGE.
